UNITED STATES PATENT OFFICE.

EMIL A. NELSON, OF ABINGTON, PENNSYLVANIA, ASSIGNOR TO BUDD WHEEL COMPANY, OF PHILADELPHIA, PENNSYLVANIA, A CORPORATION OF PENNSYLVANIA.

MACHINE FOR ROLLING METALLIC DISKS.

Application filed October 2, 1923. Serial No. 666,122.

My invention relates to improvements in machines for rolling metallic disks and has to do more particularly with disk-rolling machines of the type in which the disk is 5 mounted on a rotating support and subjected to the action of rolls which are applied to the disk under pressure and traversed radially of the disk as the table rotates.

The chief object of my present invention 10 is to provide a machine for rolling metallic disks in which the rolls are applied to the surface of the disk with a yielding pressure so as to compensate for abnormal inequalities in the disk and excessive variations in 15 its gauge or thickness.

A further object of my invention is to provide a machine of the type described which is particularly suitable for cold-rolling disks which have been tapered or formed 20 previously in order to improve the surface thereof.

A further object of my invention is to provide a disk-rolling machine, of the type referred to, provided with automatic mechanism for applying the rolls to the disk under 25 a spring pressure at predetermined intervals.

A further object of my invention is to provide a disk-rolling machine of the type 30 referred to having cam mechanism for traversing the rolls radially of the disk at predetermined intervals and for causing the rolls to be applied to the disk, under spring pressure, at suitable intervals in the operation 35 of the machine.

Further objects, and objects relating to details and economies of operation and construction, will definitely appear from the detailed description to follow. In one instance, I accomplish the objects of my invention by the devices and means set forth in the following specification. My invention is clearly defined and pointed out in the appended claims. A structure constituting a 45 preferred embodiment of my invention is illustrated in the accompanying drawings, forming a part of this specification, in which:

Fig. 1 is a view in front elevation of a 50 machine embodying my invention.

Fig. 2 is a view of the machine in side elevation.

Fig. 3 is a vertical, sectional view through the machine, taken on the line 3—3 of Fig. 2.

Fig. 4 is an enlarged view, partly in sec-

tion and partly in side elevation, of the rotating table for supporting the disk, the rolls and the roll-carriers.

Fig. 5 is a detail, sectional view taken on the line 5—5 of Fig. 1. 60

Fig. 6 is a view in side elevation of the cams and parts actuated thereby for imparting radial movements to the rolls.

Fig. 7 is a view of the parts shown in Fig. 6, looking from the left-hand side of 65 said figure.

Fig. 8 is a view in side elevation of the cam and toggle mechanism actuated thereby for raising and lowering the carriage on which the rolls are mounted, and 70

Fig. 9 is a view of the parts shown in Fig. 8, looking from the left-hand side of 75 said figure.

In the drawings, the same reference numerals refer to the same parts throughout the several views, and the sectional views are taken looking in the direction of the arrows at the ends of the section lines.

It has been proposed, heretofore, to provide a machine for rolling disks, of the type referred to, in which the blank to be rolled is mounted on a rotating table and acted upon by a pair of rolls mounted in roll carriers and supported by a carriage so that these rolls may be traversed radially of the disk. This carriage has been so mounted that it can be positively raised or lowered so as to facilitate the removal of a rolled disk from the table and the feeding of a blank thereto. It has been proposed to move 80 the carriage toward and away from the table by toggle mechanism connecting the carriage and points fixed with respect to the frame of the machine, and cam mechanism has been suggested for actuating said toggle mechanism at the proper intervals and causing the rolls to move radially of the disk at proper instants in the operation of 85 the machine.

In general, my invention consists in applying the rolls to the rotating blank under spring pressure, which will permit the rolls to yield somewhat in case of abnormal variations or inequalities in the disks or in case of accidental meeting of the rolls and the 90 table, and I propose to accomplish the purposes of my invention by providing a carriage, which may be raised and lowered with respect to the rotating table and which carries the rolls, and a toggle mechanism for 95 100 105 110

actuating the carriage which is connected to the carriage and to parts which are not rigidly fixed with respect to the frame of the machine, but are connected thereto through 6 springs, so that spring pressure is impressed upon the toggle mechanism but such parts may yield under the spring pressure in case it should be necessary due to variations in thickness.

10 Referring to the numbered parts of the accompanying drawings, in which I have shown a machine constructed in accordance with my invention, the base or frame, 10, of the machine, is provided with columns, 11, 15 at the four corners thereof. These columns, 11, have a longitudinal passage therein to receive the guide rods, 14, which extend therethrough and also through the passageways, 12, formed in the base, 10. A bushing, 13, is inserted in each passage, 12. The lower end of each rod, 14, is reduced in diameter forming the smaller lower portion, 15, which projects below the portion of the base through which it extends, as shown in Figs. 20 1, 2 and 5. The bushing, 13, is retained in place by the nut, 17, which is screwed into the lower end of the bushing and surrounds the reduced portion, 15, of the rod, 14. The head, 18, of the nut engages the lower end of 25 the bushing, 13, (see Fig. 5) and is provided with suitable apertures to receive a tool by means of which the nut may be adjusted. The shoulder, 16, of the rod, 14, is adapted to engage the upper end of the nut, 17, which 30 thus acts as a stop to limit the downward movement of the rod, 14, with respect to the base or frame of the machine. A loose ring, 19, surrounds the head of the nut, 17, and engages the shoulder, 9, of the base, 10. The 35 smaller portion, 15, of each rod, 14, extends downwardly through the nut, 17, and through a washer, 20, which engages the lower surface of the ring, 19. The portion, 15, of the rod also extends through a second 40 washer, 22, and a comparatively stiff and heavy spring, 21, is interposed between the washers, 20, and 22, the latter being held in place by the nuts, 23, screwed on the lower end 45 of the rod, 14. This construction is employed at each of the four corners of the base, 10, and it will be seen that the rods, 14, are not rigidly fixed with respect to the base or frame of the machine, but are connected thereto through the heavy springs, 21, so 50 that, when a comparatively heavy pressure is applied, these rods may yield and move with respect to the base.

55 The rotating table, 24, is provided with a face, 25, which is adapted to support the disk, A, and is shaped to conform to the cross-section of the disk which is to be rolled on the machine. The machine illustrated is designed for rolling tapered disks, and the face, 25, is therefore slightly conical and concave. The table, 24, is provided with a

centering pin, 26, which is adapted to extend through a central opening in the disk, A. The table, 24, is mounted so as to rotate freely, being journaled on the base, 10, through the roller bearings, 27, and driven 70 by a gear, 28, which is driven from shaft, 29, carrying the pulley, 30, over which the belt, 31, runs, said belt being connected with any suitable source of power.

75 The carriage, 32, is slidably mounted on the guide rods, 14, being provided with vertical bores or passageways at its four corners through which the rods, 14, extend. The upper ends of the rods, 14, are rigidly connected by the cross bars, 33, and the cross rods, 34, the latter serving as journal shafts or rods on which certain of the operating parts are journaled. The disk, A, supported on the rotating table, 24, is acted upon by the rolls, 35, each of which has a cylindrical 85 portion, 36, and a frusto-conical portion, 37. These rolls are mounted in roll carriers, 38, which are arranged to slide in the guideways, 39, extending transversely of the lower surface of the carriage, 32. Each roll carrier, 90 38, has a pair of spaced depending arms, 40 and 41, in which the roll shaft, 42, is journaled. The inner end of each roll shaft is journaled in a bearing, 43, carried by the arm, 40, of the carrier, while the outer end of the roll shaft is journaled in a bearing, 44, carried by a member, 45, secured to the arm, 41. The roll, 35, is fastened to the roll shaft between the depending arms, 40 and 41, (see Fig. 4). A cap, 46, is secured to the arm, 41, of each carrier, and to the members, 45, and it has a depending ear, 47. The ears, 47, on the respective caps, 46, are connected through links, 48, to the threaded pins, 49, which are mounted in the lower 105 ends, 50, of the bell-crank levers, 53, and are adjustably secured thereto by the nuts, 51 and 52.

110 The bell-crank levers, 53 and 53', are pivoted on the carriage, 32, at 54, and the arms, 55, of said bell cranks extend inwardly toward each other and are connected to the link, 56, which in turn is connected to the lower end of the link, 57. A rocker, 59, is 115 journaled on a cross-rod 60, carried by the carriage, and is provided with rollers, 61 and 63, which engage the edges of the cams, 62 and 64. The upper end of the link, 57, is connected to the rocker, 59, at 58. The cams, 62 and 64, are fastened on the cam shaft, 65, 120 which is driven by a worm gear (not shown) housed within the casing, 66, and meshing with a worm (not shown) on the shaft, 67. The latter is driven by belt, 69, connected with any suitable source of power and running over the pulley, 68, on shaft, 67.

125 The sleeves or knuckle members, 70, are journaled on the cross-rods, 34, and each sleeve has two pairs of arms, 71, depending therefrom and connected by the links, 72, to 130

the carriage, 32. An arm, 73, extends upwardly from each of the sleeves, 70, and the upper ends of these arms are connected by the cross bar, 74. One of the arms, 73, 5 is connected by means of an adjustable rod, 75, with a rocker member, 76, which is journaled on the cross rod, 77, supported by the carriage, 32, and has a pair of rollers, 78 and 79, engaging the edge of cam, 80, which is 10 fastened on the cam shaft, 65.

From the foregoing description of the parts, the operation of the machine will readily appear. The disk, A, to be rolled, is placed upon the rotating table, 24, with 15 the centering pin, 26, extending through the central opening in the disk. This is done while the carriage, 32, is raised to remove the rolls, 35, from the table. When the disk is in place on the table the carriage, 32, is 20 forced downwardly so as to apply the rolls, 35, to the disk under the pressure of springs, 21, and the roll-carriers are moved so as to shift the rolls, 35, radially outward of the disk. The carriage, 32, is then released and 25 raised so as to remove the rolls from the disk, and, while the carriage is raised, the rolls are moved toward each other to their initial position. The cams, 62 and 64, operating on the rollers, 61 and 63, of rocker 30 59, actuate the bell-crank levers, 53, 53' to shift the rolls, 35, radially with respect to the disk. The arms, 71, on sleeves or knuckle members, 70, together with the links, 72, form a series of toggle linkages, 35 one at each of the four corners of the carriage, for forcing the carriage toward the rotating table to apply the rolls to the disk under pressure. The cross rods, 34, on which the sleeves or knuckle members, 70, 40 are journaled, are not fixed with respect to the frame of the machine since they are connected to the upper ends of the rods, 14, which are yieldingly-connected to the frame of the machine through the springs, 21. 45 When the toggle linkages are straightened out (as shown in Fig. 8) the pressure of the springs, 21, is exerted on the carriage, 32, to force the rolls against the disk. If the resistance to the action of the rolls exceeds 50 the pressure of the springs, 21, the cross rods, 34, may yield upwardly. This construction has certain decided advantages in that it is not necessary to be so careful about variations in thickness of the disks or 55 blanks which are to be rolled in the machine. In case a blank, which is thicker than those for which the machine has been set, is inserted in the machine, the springs, 21, will yield, and the blank will be rolled; whereas, if the cross rods, 34, were fixed, it is likely that the machine would be wrecked in the attempt to roll too thick a disk. The toggle linkages are actuated through the arms, 73, by the rocker, 76, the rollers, 78 60 and 79, on which, are engaged by the cam, 80, on the cam shaft, 65. The cams, 62, 64 and 80, operate to actuate the carriage and roll-carriers automatically in a predetermined sequence and at predetermined intervals. These cams are such that, assuming the parts to be in the position shown in Figs. 1 and 2, the rolls, 35, are, first, shifted radially outward with respect to the table. When the rolls reach the limit of their outward movement, there is a slight dwell and, 70 at that instant, the carriage, 32, is raised. The rolls, 35, are then moved radially to their initial position. It is to be observed that the cams are such that the return movement of the rolls is considerably faster 75 than the outward movement. When the rolls have returned to their initial position, the cam, 80, acts on the toggle linkages to move the carriage, 32, toward the table and to force the rolls against the blank under the working pressure imparted by the springs, 21.

This machine is particularly suitable for cold-rolling disks or blanks which have been tapered, or given a desired cross section, 80 previously. It has been found that the cold-rolling of such disks or metal blanks gives them a surface which is very desirable for painting and finishing, even though there is practically no reduction in thickness 85 of the metal or change in cross section. This machine has been found to do such cold-rolling very satisfactorily. It is useful, however, in rolling tapered disks or other metal shapes from blanks of uniform cross 90 section. I have illustrated a cam mechanism for traversing the rolls radially, and raising and lowering the rolls at proper intervals, but, of course, I am not to be restricted to cam mechanism, as any other suitable means 95 may be employed for this purpose.

I am aware that the machine for rolling disks which is illustrated in the accompanying drawing may be changed considerably without departing from the spirit of my invention and, therefore, I claim my invention broadly, as indicated by the appended 100 claims.

Having thus described my invention, what I claim as new and useful and desire to secure by Letters Patent is:

1. A machine of the class described comprising a rotatable support for the blank to be rolled, a roll adapted to act on the blank, means for applying said roll to the upper surface of said blank under spring pressure, and means for traversing said roll radially of the blank.
2. A machine of the class described comprising a rotatably mounted table adapted to support the blank to be rolled, a plurality of rolls, means for applying said rolls to the upper surface of said blank under spring pressure, and means for traversing said rolls radially of the blank.

3. A machine of the class described comprising a support for the blank to be rolled, a roll co-operating with said support, a spring-pressed toggle for maintaining a working pressure between said roll and support during the rolling operation, and means for automatically breaking said toggle after the completion of the operation to permit the removal of the rolled blank. 5
10. 4. A machine of the class described comprising a support for the blank to be rolled, a shiftable roll co-operating with said support, a spring-pressed toggle for applying pressure between said roll and the support during the rolling operation, and cam means acting automatically at the completion of the rolling operation to break the toggle and permit the removal of the rolled blank. 15
5. A machine of the class described comprising a support for the blank to be rolled, a co-operating roll adapted to be moved crosswise of the support in contact with the blank, spring means for maintaining a working pressure between the roll and the support during the rolling operation, and means for automatically separating said roll and support and restoring the roll to starting position after the completion of each rolling operation. 20
30. 6. A machine of the class described comprising a support for the blank to be rolled, a co-operating roll, means for moving the roll into contact with the blank and maintaining said roll in contact therewith under spring pressure, means for shifting the roll crosswise of the blank during the rolling operation, and means for automatically causing the raising of the roll from the blank after the completion of the rolling operation and the return of the roll to the initial or starting position after having been raised. 35
7. A machine of the class described comprising a support for the blank to be rolled and a roll-carrying frame movable relatively toward and from each other, a pair of rolls carried by the frame, one at each side of the center of the blank, means for imparting a relative movement to the frame and support, spring means for creating a working pressure between said rolls and the support, and means for moving the rolls oppositely and radially of the blank in a progressive manner while operating on the blank to effect changes therein. 45
50. 8. A machine of the class described comprising a support for the blank to be rolled and a roll-carrying frame relatively movable toward and from each other, a pair of rolls carried by the frame, one at each side of the center of the blank, means for imparting relative movement to the frame and support and for urging them together under spring pressure, and cam means for moving the rolls oppositely and radially of the blank in a progressive manner while operating on the blank to effect changes therein. 55
5. of the blank in a progressive manner while operating on the same to effect changes of form therein. 60
9. A machine of the class described comprising a rotating support for the blank, a roll carrier movable toward and from said support, rolls carried by said carrier and co-operating with the blank, means for moving said carrier toward the support and applying the rolls to the blank under spring pressure, and means for moving the rolls radially of the blank. 65
10. A machine of the class described comprising a rotating support for the blank, a roll co-operating with said support, spring means for moving said roll toward the support to apply pressure to the blank, means for moving the roll radially of the blank, and means for automatically moving the roll away from the blank when the roll reaches a predetermined point in its radial movement. 70
11. A machine of the class described comprising a rotating support for the blank, a roll co-operating with said support, spring means for moving said roll toward the support to apply it to the blank under spring pressure, means for moving the roll away from the support, means for moving the roll radially of the blank, and means for automatically returning said roll to the central portion of the blank. 75
12. A machine of the class described comprising a rotating support for the blank, a frame supported above said support for vertical movement with respect thereto, a pair of roll carriers slidably mounted for horizontal movement in said frame, a roll carried by each of said carriers and adapted to engage a blank on said support, means for moving the frame toward and away from said support at predetermined intervals, spring means for pressing said rolls against the blank, and means for moving said carriers horizontally with respect to the said support. 80
13. A machine of the class described comprising a rotating support for the blank to be rolled, a roll adapted to operate on a blank on said support, cam mechanism for raising, lowering and moving said roll radially of the blank in a predetermined sequence and at predetermined intervals, and spring means exerting a working pressure upon said roll. 85
14. A machine of the class described comprising a rotating support for the blank to be rolled, a pair of rolls adapted to operate on a blank on said support, spring means for exerting a working pressure upon said rolls, and cam mechanism for raising, lowering and moving said rolls radially of the blank, toward and from each other, in a predetermined sequence and at predetermined intervals. 90
15. 120
- 125
- 130

15. A machine of the class described comprising a rotating table, a carriage vertically movable with respect to said table, a roll carried by said carriage and adapted to be moved transversely thereof, spring pressure means acting on said carriage, cam mechanism for raising and lowering said carriage, and cam mechanism for moving said roll transversely of the carriage. 70
16. A machine of the class described comprising a rotating table adapted to support a blank to be rolled, a carriage vertically movable with respect to said table, spring pressure means acting on said carriage, a roll carried by said carriage and adapted to operate on a blank supported on said table, and mechanism carried by said carriage for raising and lowering it and moving the roll radially of the table. 75
17. A machine of the class described comprising a rotatably mounted table adapted to support a blank to be rolled, a carriage vertically movable with respect to the table, a pair of rolls carried by said carriage and adapted to operate on a blank supported on said table, spring pressure means acting on said carriage, and cam means for raising and lowering said carriage with respect to the table, said cam means being such as to lock the carriage in raised and lowered positions for predetermined intervals. 80
18. A machine of the class described comprising a frame, a rotatably mounted table adapted to support a blank to be rolled, a carriage vertically movable with respect to the table, a roll carried by said carriage and adapted to operate upon a blank supported on the table, an abutment, spring pressure means interposed between said frame and said abutment, and means for raising and lowering said carriage including a toggle linkage connecting said carriage and said abutment and means for actuating said toggle linkage. 85
19. A machine of the class described comprising a frame, a rotatably mounted table adapted to support a blank to be rolled, a carriage vertically movable with respect to the table, a pair of rolls carried by said carriage and adapted to operate on a blank supported on said table, a pair of knuckle pivots connected to said frame through means including one or more springs, a knuckle member journaled on each pivot, arms on said knuckle members, links connecting said arms with the carriage, and means for rocking said knuckle members on said pivots. 90
20. A machine of the class described comprising a frame, a rotatably-mounted table adapted to support a blank to be rolled, a carriage vertically movable with respect to the table, a pair of rolls carried by said carriage and adapted to operate on a blank supported on the table, a pair of knuckle pivots connected to the frame through means including one or more springs, knuckle members journaled on said pivots, downwardly-extending arms on said knuckle members, links connecting said arms and the carriage, upwardly-extending arms on said knuckle members, means connecting said upwardly-extending arms whereby said knuckle members are forced to turn in unison, and means for rocking said knuckle members on their pivots. 95
21. A machine of the class described comprising a frame, a rotatably mounted table adapted to support a blank to be rolled, a carriage vertically movable with respect to the table, a pair of rolls carried by said carriage and adapted to operate on a blank supported on the table, a pair of pivots connected to the frame through means including one or more springs, knuckle members journaled on said pivots, connections between said knuckle members and the carriage, a rocker member journaled on the carriage, a cam acting on said rocker member, and connections between said rocker member and the knuckle members. 100
22. A machine of the class described comprising a frame, a rotatably-mounted table adapted to support a blank to be rolled, a carriage vertically movable with respect to the table, a pair of rolls carried by said carriage and adapted to operate on a blank supported on the table, pivot members connected to the frame through means including one or more springs, a pair of knuckle members journaled on said pivot members, each of said knuckle members having two pairs of spaced arms, links connecting said arms with the four corners of the carriage, and means for rocking said knuckle members in unison on their pivots. 105
23. A machine of the class described comprising a base, a rotatably-mounted table adapted to support a blank to be rolled, guide rods extending vertically from said base and connected thereto through means including pressure springs, cross rods secured to and connecting the upper ends of said guide rods, a carriage vertically movable on said guide rods, a roll carried by said carriage and adapted to operate on a blank supported on the table, knuckle members journaled on said cross rods and connected to said carriage, and means supported by said carriage for rocking said knuckle members on their bearings. 110
24. A machine of the class described comprising a base, a plurality of guide rods extending vertically from said base and slidably mounted therein, pressure springs interposed between parts of said base and the lower ends of said guide rods, a carriage vertically movable on said guide rods, a rotatable support carried by said base and adapted to support a blank to be rolled, a roll carried by said carriage and adapted to 115
- 120
- 125
- 130

act on the blank, toggle linkages connecting said carriage and the upper ends of said rods, and means for actuating said linkages.

25. A machine of the class described comprising a base, a support rotatably mounted on said base and adapted to support a blank to be rolled, vertical guide rods slidably mounted in said base, a plurality of springs compressed between parts of said base and the lower ends of said rods, a carriage vertically movable on said rods, a transversely-shiftable roll carried by said carriage and adapted to operate on the blank, and means carried by said rods and acting on the carriage to raise and lower the same.

26. A machine of the class described comprising a base, a support rotatably mounted on said base and adapted to support a blank to be rolled, vertical guide rods slidably mounted in said base, a plurality of springs compressed between parts of said base and the lower ends of said rods, a carriage vertically movable on said rods, a transversely-shiftable roll carried by said carriage and adapted to operate on the blank, and cam-actuated means carried by said rods and acting on the carriage to raise and lower the same.

27. A machine of the class described comprising a base, a support rotatably mounted on said base and adapted to support a blank to be rolled, vertical guide rods slidably mounted in said base, a plurality of springs compressed between parts of said base and the lower ends of said rods, a carriage vertically movable on said rods, a transversely-shiftable roll carried by said carriage and adapted to operate on the blank, cross rods connecting the upper ends of certain of the said guide rods, a pair of knuckle members journaled on said cross rods and provided with arms, links connecting said arms and the carriage, and means for actuating said knuckle members.

28. A machine of the class described comprising a base provided with a plurality of

vertical passageways therein, a bushing in each passageway, guide rods slidably-mounted in said bushings and extending vertically above the base, said guide rods having lower ends of reduced diameter forming shoulders thereon, nuts screwed into said bushings and adapted to be engaged by rods, washers mounted on the lower ends of said rods, nuts screwed on said rods and holding said washers in place, springs interposed between said washers and parts of the base, a support for a blank to be rolled rotatably mounted on said base, a carriage slidably mounted on said rods, a transversely-shiftable roll carried by said carriage and adapted to operate on the blank, and means carried by said rods for raising and lowering the carriage.

29. In a machine of the class described, the combination of a base provided with a plurality of vertical passageways therein, a bushing mounted in each passageway, a guide rod slidably mounted in each bushing and extending vertically above the base, said guide rod having a shoulder thereon normally located within the bushing, a nut screwed into the lower end of the bushing and adapted to be engaged by a ring surrounding the end of said nut and engaging a part of the base, a pair of washers loosely mounted on the lower end of said rod, the uppermost washer engaging said ring, a spring compressed between said washers, and retaining means on the lower end of said rod engaging the lowermost washer.

30. A machine of the class described comprising a rotating support for the blank, a roll cooperating with said support, means for moving the roll radially of the blank under pressure, and means for precluding the application of a pressure greater than a predetermined amount.

In testimony whereof I affix my signature.

EMIL A. NELSON.
